UNITED STATES PATENT OFFICE

CARL F. BLATTNER, OF LOS ANGELES, CALIFORNIA, ASSIGNOR TO MISSION DRY CORPORATION, LTD., OF LOS ANGELES, CALIFORNIA, A CORPORATION OF DELAWARE

DESIGN FOR A DISPENSING STAND

Application filed April 30, 1930. Serial No. 35,449. Term of patent 3½ years.

To all whom it may concern:

Be it known that I, CARL F. BLATTNER, a citizen of the United States, residing at Los Angeles, in the county of Los Angeles and State of California, have invented a new, original, and ornamental Design for a Dispensing Stand, of which the following is a specification, reference being had to the accompanying drawings, forming part thereof.

Fig. 1 is a side elevation and Fig. 2 is a top plan view, on a reduced scale, of a dispensing stand, showing my new design.

I claim:

The ornamental design for a dispensing stand, as shown.

CARL F. BLATTNER.
